UNITED STATES PATENT OFFICE.

GEORGE SCHUHMAN, OF READING, PENNSYLVANIA.

STARTING OR REVERSING MECHANISM FOR STEAM-ENGINES.

SPECIFICATION forming part of Letters Patent No. 613,783, dated November 8, 1898.

Application filed November 3, 1897. Serial No. 657,253. (No model.)

To all whom it may concern:

Be it known that I, GEORGE SCHUHMAN, a citizen of the United States, residing at Reading, county of Berks, State of Pennsylvania, have invented certain Improvements in Starting or Reversing Mechanisms for Steam-Engines, of which the following is a specification.

My invention relates especially to slide-valve steam-engines; and my object is to provide an improved mechanism adapted to permit the starting or reversing of the engine without operating the main valve, which in the case of large engines it is difficult for the operator to move as required. Valves have heretofore been applied to engines for this purpose, by means of which steam has been admitted to and exhausted from opposite ends of the cylinder independently of the main valves.

My invention consists in the improved construction and arrangement of mechanism, which is fully described in connection with the accompanying drawings.

Figure 1 is a cross-sectional view of a portion of an engine-cylinder, showing my improved mechanism applied thereto, the section being taken on the line $x-x$ of Fig. 2. Fig. 2 is a plan view of the same. Fig. 3 is a longitudinal vertical section of the valve and valve-chamber, taken on the line $y-y$ of Fig. 2 and showing also in cross-section the portion of the cylinder-casting to which it is connected. Fig. 4 is a sectional plan view of an engine-cylinder, showing my improved mechanism attached thereto.

A represents the cylinder proper of an ordinary steam-engine; B, the steam-chest; D D', the steam-inlet to the chest; C, the main-valve seat; E, the steam-ports connecting the opposite ends of the cylinder to the steam-chest, and F the exhaust-port. The flow of steam through the ports E and F is controlled, as usual, by a slide-valve.

To enable the engine to be started or reversed without moving the main valve, which, as has been stated, it is often difficult to do, it is necessary to provide independent means for admitting or releasing steam to and from the opposite ends of the cylinder. In my improved construction this is provided for as follows: Openings e are made through the exterior wall of the cylinder-casting into the

ports E, respectively, at a convenient location between the steam-chest and the cylinder, and a passage-way f is also provided 55 from the exhaust-port F through the double wall of the cylinder, opening exteriorly between the openings e from the steam-ports, this passage-way being formed, as shown, by a pipe which passes through the steam-inlet 60 D and is tightly secured in the outer and inner walls d and d' of the latter. Suitable steam-tight seats e' and f' are provided around each of the openings e and f for a valve-casing H, which is arranged to connect these several 65 openings. The casing H is formed with a cylindrical valve-chamber h and with hollow lateral extensions H' and H'', the outer ends of which are formed with finished faces adapted to rest upon the seats e' and with bolting-flanges h³ 70 h³, by means of which the complete casing is removably secured to the cylinder-casting. These lateral extensions H' H'' are formed with passage-ways h' h', which serve to connect the port-openings e with the intermediate valve-chamber h. This chamber also communicates, 75 through a central passage h², with the passage-way f to the exhaust-port F, a suitable joint being formed also on the seat f'. A supply-pipe I for live steam connects with the top of 80 the chamber, and a three-way valve J is located within it, the latter being arranged to close both of the passage-ways h' h' when in central position. This valve is operated by means of a spindle K, passing through a stuffing-box K', and a suitable lever mechanism K'. When it is desired to admit steam to the end of the cylinder with which the port E connects, for instance, in order to move the piston toward the opposite end, the valve J is 85 turned so as to throw the port E into communication with the supply-pipe I, this movement at the same time throwing the opposite port E into communication with the exhaust-port F. The engine is thus started in the 90 proper direction, after which the main valve will automatically control it.

By arranging the port-openings e and f as described and connecting the same by means of a single casting having the valve-chamber 100 and the required passage-ways formed therein and connecting directly with said openings I am able to produce a perfectly satisfactory communication between the several ports and

the valve-chamber, while at the same time permitting of easy removal for repairs or renewal and presenting an extremely neat and mechanical appearance.

5 What I claim is—

In a steam-engine the combination with a cylinder having separate steam-ports extending from its opposite ends to the steam-chest, an intermediate exhaust-port, and passages 10 from said several ports opening exteriorly substantially as described, of an integrally-formed valve-casing having ways therein com-

municating directly with each of said passages and seats around the openings thereof, an independent steam-inlet to said casing, and a 15 three-way valve therein with mechanism for operating the latter substantially as and for the purpose set forth.

In testimony whereof I affix my signature in presence of two witnesses.

GEORGE SCHUHMANN.
